[57] CLAIM

The ornamental design for a foldable trash container for
use on a car as shown and described.

DESCRIPTION

FIG. 1 is a top perspective view of a foldable trash
container for use on a car showing my new design;
FIG. 2 is a plan view thereof in an unassembled condi-
tion;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

FIG. 1

FIG. 3

FIG. 4

FIG. 5

FIG. 6

FIG. 7

FIG. 8
